UNITED STATES PATENT OFFICE.

EUGENE A. LAHIERE, OF WASHINGTON, DISTRICT OF COLUMBIA.

TOY.

1,108,913.

Specification of Letters Patent.

Patented Sept. 1, 1914.

Application filed January 27, 1914. Serial No. 814,621.

To all whom it may concern:

Be it known that I, EUGENE A. LAHIERE, citizen of France, residing at Washington, in the District of Columbia, have invented 5 certain new and useful Improvements in Toys, of which the following is a specification.

My invention relates to improvements in toys, particularly to toys of the type employing an endless circular track, together with a train of cars movable upon the track, and means for moving the cars, one object of my invention being the provision of means for manually moving the cars in such 10 a manner that they may be moved ahead or back as preferred, or stopped at any desired point along the track.

More specifically, the object of my invention is the provision of a toy embodying 20 a support, board or table, upon which the track and cars are mounted, the upper face of the board being ornamented, preferably in such a way as to provide a scenic effect both about and within the track.

One object of my present invention is the construction of means for manually operating 25 the cars so arranged that all operating mechanism, save the hand crank by means of which such mechanism is driven, will be hidden from view, and further in such a manner that the cars may be made to uninterruptedly pass through tunnels or other obstructions.

A still further object of my invention is 30 to so construct the board constituting the support or table of the toy that it may be readily folded for storage or shipment. In this connection, the train operating means is so constructed that it may be readily 35 taken apart and removed from the board to permit folding of the board and more convenient packing of the toy as a whole.

With these and other objects in view, my 40 invention will be more fully described, illustrated in the accompanying drawings, and then specifically pointed out in the claims which are attached to and form a part of this application.

In the drawings:—Figure 1 is a perspective view of my improved toy ready for 45 operation; Fig. 2 is a sectional view taken on the line 2—2 of Fig. 1, the superstructure constituting the scenic effect of the toy, being removed to permit a clearer showing of 50 the mechanical structure itself; Fig. 3 is a

side elevation, partially in section, of the board or platform of the toy in folded position; Fig. 4 is a perspective view of the underside of the board in open position; Fig. 5 is a fragmentary perspective view 60 of the operating mechanism for moving the train about the circular track, said mechanism being shown disconnected from the remainder of the toy.

Corresponding and like parts are referred 65 to in the following description and indicated in all the views of the drawings by the same reference characters.

The board or platform of the toy proper is indicated as a whole by the numeral 10 70 and the preferred form of my invention includes two symmetrically formed body portions 11 and 12 each rectangular in shape and so proportioned that when their more extensive edges are hingedly connected, as 75 shown at 13, and the portions swung to extended position, the resultant board 10 is square. The edges of the portions 11 and 12 may be ornamented with any suitable strips of molding or trim 14, if desired. 80

The body portions 11 and 12 are provided adjacent their free edges with supporting strips or braces 15 which, when the board is in use, serve to space the same somewhat above the table or other support upon which 85 it may be placed and which, when the board is folded, engage one upon the other as shown in Fig. 3. The hinges 13 as shown, are so constructed that when the board is extended, the hinged edges of the board sections 11 and 12 will abut evenly against each 90 other while, when the board is folded to bring its supporting braces 15 in superimposed position, the board sections will extend in parallel spaced relation to each 95 other.

The board sections 11 and 12 are provided with additional braces 16 spaced from the hingedly connected edges of said sections. These latter braces have their lower faces 100 mortised as shown at 17 and 18 to receive the cross braces 19 and 20, respectively, the first of these braces being located centrally of the board and the latter at the edge thereof. These cross braces are approximately one-half the thickness of the braces 16 and therefore a space is provided between the braces and board when the board is in extended position. These cross braces are secured to the braces 16 by means of hinges 21 and 110

when the board is in extended position are fastened at their free ends by spring catches, indicated as a whole by the numeral 22 in such a manner as to prevent accidental folding of the board. These catches each include a resilient hook member 23 secured to the board section 12 and a spring tongue 24 secured to the adjacent cross brace.

10 The board or platform is provided centrally with a circular opening 25, this opening being formed by cutting away a portion of the abutting edges of the board sections 11 and 12 and the cross brace 19, which is located beneath this opening, is provided 15 with a relatively small opening 26. In like manner, the cross brace 20 is provided with a small opening or bore 27 in alignment with an opening formed in the abutting edges of the board sections 11 and 12.

20 The openings 25 and 27 of the cross braces are provided with metallic bushings 28, the lower ends of which are flared somewhat as shown, and shafts 29 and 30 pass upwardly through these bushings and through the 25 openings in the board proper, these shafts having their lower ends enlarged to limit their upward movement. Loosely mounted upon the shaft 29 is a pulley wheel 31 including a hub portion 32, spokes 33 and a 30 peripherally grooved rim 34, the hub, adjacent one end, being formed with a squared socket 35 in alignment with one of the spokes and such spoke being provided with a sleeve 36 and set bolt 37. A spacer sleeve 38 surrounds the shaft immediately above the pulley 31 and bearing upon the upper end of the spacer sleeve is a disk 39, this disk being secured against displacement by a washer 40 and nut 41 threaded upon the upper end 40 of the shaft 29.

A pulley wheel 42, having a grooved peripheral face, is secured upon the shaft 30 by a key 43 or other suitable means, this pulley being located between the cross brace 20 45 and the board 10 and the upper end of the shaft 30, which extends above the board 10, is provided with a hand crank 44 secured to the shaft by a set bolt 45 or other suitable 50 fastening means. A crossed belt 46, preferably in the form of a cable, is trained about the pulleys 31 and 42, whereby rotation of the pulley 42 by the hand crank 44 will cause rotation of the pulley 31. The pulley 31 being freely mounted upon the shaft 29 55 will not, however, rotate such shaft and its disk 39. The disk 39 is proportioned to cover the larger part of the upper surface of the board or support of the toy and secured to the board in any suitable manner and 60 surrounding this disk is an endless, preferably, but not necessarily, circular track 46' adapted to receive a train of toy cars 47 including a toy locomotive 48. The rails of this track are, of course, broken at the hinged joint of 65 the board between the sections 11 and 12 in

order to permit proper folding of the board, as previously explained.

The cowcatcher 50 of the locomotive 48 is provided in its top with an opening 51 and in one side with an opening 52. A connecting member 53 has one end offset upwardly as at 54 and curved to form a terminal eye 55 proportioned to pass through the opening 52 and to receive a locking pin 56, the stem of which passes through the opening 51 and the head of which seats upon the top of the cowcatcher. The body portion of this member extends radially beneath the disk 39 and has its inner end offset upwardly as at 57 and squared to pass through the sleeve 36 and into the hub socket 35, being secured in place by the set bolt 37.

It will of course be apparent that turning of the hand crank will act through the pulleys 42 and 31 to swing the member 53 and so move the locomotive and attached cars, the direction of movement of the train and its speed being dependent upon the direction and speed with which the hand crank is turned.

In order to lend increased interest to the toy, the upper surface of the board is preferably decorated in any suitable manner, some such scenic effect as that shown being preferred. The manner of carrying out this decoration does not in any way constitute part of my invention and but little description of such decoration is therefore necessary. The various buildings, fountains and plots of lawn shown may be made of any 90 suitable material and permanently attached to the upper face of the board or they may be made of any suitable material and fixed to sheets of cardboard or other material which are either permanently or detachably 95 mounted upon the board. The latter is the form of construction illustrated in Fig. 1, the decorations being formed in three sections, a circular section 58 being provided for the disk 39 and two semi-annual sections 59 being provided to surround the circular track 46. In any case, one of the outer sections 59 should be provided with an arched portion 60, the free inner end of which will engage upon the upper face of 100 the disk 39 when the toy is assembled to provide a tunnel or cave through which the 105 train may pass, this greatly increasing the realistic effect of the toy. If desired, the sections 59 or the section 58 may be provided 110 with manually movable toy figures 61 which may be changed from one part of the toy 115 to another at the will of the user.

From the foregoing description, the construction and operation of my improved toy 120 will be readily understood and no further description is necessary. It will be understood, however, that I do not wish to limit myself to the specific details of construction, illustrated in the drawings and set forth in 125 130

the specification, as various minor changes, within the scope of the appended claims may be made at any time without in the slightest degree departing from the spirit 5 of my invention. For instance, the member 53 preferably consists of a rod 62 and sleeve 63 in which one end of the rod telescopes, the sleeve being tapped to receive a set bolt 64. With such a construction, the member 10 53 may be adjusted to proper length for a circular track and then clamped in adjusted position. On the other hand, if the track is non-circular, the set bolt may be removed and the train still moved about the track by 15 the member 53, the rod 62 sliding back and forth in the tubular member 63 to compensate for irregularities in the track curvature.

Having thus described the invention, what 20 is claimed as new is:

1. A toy including a board or platform, a track on the platform, a pulley mounted adjacent the track and beneath the platform, means for rotating the pulley, a member extending from the pulley, a wheeled figure movable on the track and provided with openings, one of which is adapted to receive the free end of the member, and a coupling pin insertible through the other opening to 30 detachably secure such member.

2. A toy including a board or platform, a track on the platform, a pulley mounted adjacent the track and beneath the platform, means for rotating the pulley, a member extending from the pulley and provided at its outer end with an eye, a locomotive movable on the track and including a cowcatcher having openings in its inner and top walls, the former being adapted to receive the outer 40 end of the member, and a coupling pin

adapted to be inserted through the opening in the upper wall of the cowcatcher.

3. A toy including a board or platform provided with an opening, a disk mounted in spaced relation above the platform, and 45 covering the opening, a track located about the disk and on the platform, a wheeled figure movable on the track, a pulley located beneath the platform and disk and a member connected at one end to the pulley 50 and extending through the opening of the platform and beneath the disk, said member being adapted at its opposite end for connection with the wheeled figure.

4. A toy including sections hingedly connected to form a board or platform, braces extending along the lower faces of the sections adjacent their hinged edges, transverse braces hingedly connected at their ends to one of the first braces and adapted for detachable connection with the other of the first mentioned braces when the board is extended to lock the board in extended position, bearings formed in the transverse braces, shafts journaled in the bearings, a 60 65 pulley freely mounted on one shaft, a pulley detachably secured to the other shaft, a belt trained about the pulleys, means for rotating that shaft having the fixed pulley, a track carried by the upper face of the platform, a wheeled figure adapted for movement along the track, and operative connection between the loose pulley and figure.

In testimony whereof I affix my signature in presence of two witnesses.
